FIG. 1.

FIG. 4.

FIG. 2.

FIG. 3.

INVENTOR.
EDWARD A. JODOIN.
BY Joseph J. O'Brien

ATTORNEY.

UNITED STATES PATENT OFFICE.

EDWARD A. JODOIN, OF SPRINGFIELD, MASSACHUSETTS.

SHIRT.

Application filed April 16, 1924. Serial No. 707,787.

To all whom it may concern:

Be it known that EDWARD A. JODOIN, a citizen of the United States of America, residing at Springfield, in the county of Hampden and State of Massachusetts, has invented certain new and useful Improvements in Shirts, of which the following is a specification.

This invention relates to improvements in shirts and one of its objects is to provide a shirt having a collar and a pair of cuffs, with a renewal facing for the collar and for each of the cuffs, or for either, which can be readily removed to expose a fresh surface to wear, after the edges of the removable surface have been worn or otherwise rendered unsightly.

With the above and other objects in view the invention comprises certain new and useful constructions, combinations and arrangements of parts, clearly described in the following specification and fully illustrated in the accompanying drawings, in which:—

Fig. 1 is a front elevation of a shirt embodying my improvements.

Fig. 2 is a plan view of one of the cuffs showing the removable facing piece.

Fig. 3 is a plan view showing the removable facing detached.

Fig. 4 is a detail sectional view on an enlarged scale.

Referring to the accompanying drawings illustrating the practical embodiment of the invention 5 designates a shirt, which comprises the usual body portion 6, the sleeves 7 and 8, and the neck band 9, which carries a permanent collar 10, suitably secured thereto. The sleeves 7 and 8 are each provided with a cuff 11 preferably of the folded type, so as to be reversible, at will of the user.

These features are old and well known. The outer layer 11^a of the cuff is exposed to rapid wear at the band 11', and when the threads begin to unravel the cuff becomes unsightly, and the user will frequently discard the shirt, which is otherwise capable of rendering considerable additional service.

50 The cuff 11 is attached to the lower end of the sleeve by means of the usual seam 12. The body of the cuff 11 is built up of two layers of material, 13 and 14, which have their edge portions inturned and secured directly to each other by means of the stitch-

ing 15, which extends along the marginal edge portion of the cuff.

Both sides of the cuff are finished in the material of which the shirt is made, and one side of the cuff looks like the opposite side. 60

The cuff is usually folded upon itself so as to present to normal wear the inner facing layer 14. When this layer is worn thread bare the shirt no longer serves its purposes for dress use. 65

Over the permanent inner facing layer 14 I secure a detachable facing layer 15, by a seam or stitching 16, which extends around the marginal edge thereof, outward of the stitching 15. 70

The cuff is formed with the usual button holes 17 and 18, which are located on one side of the double cuff body, and button holes 19 and 20 which are located on the opposite side thereof. When the cuff is folded upon itself the button hole 17 will register with the button hole 18 and the button hole 19 will register with the button hole 20, in the usual manner. 75

The extra facing layer 16 is formed with 80 button holes 17' and 18', which register, respectively with the button holes 17 and 18, and is further formed with the button holes 19' and 20', which register with the button holes 19 and 20, at all times when the facing 85 layer 16 remains attached to the cuff. The end portions of each button hole of the facing layer 16 are secured by the stitching 21 to the end portions of the adjacent button holes, so that no local separation will take 90 place between the layer 16 and the cuff.

The cuff thus finished presents to the user the general finish of a standard cuff, and the extra layer can only be detected by close examination by an expert. 95

When it is desired to remove the extra layer 16 the part worn through or worn badly is opened up and the layer 16 is folded back upon itself, and the attaching stitching 16' is ripped or cut, and the button hole stitching 21 is also cut. The layer 16 may be then removed and the cuff will have a fresh layer for exposure to wear in regular use. 100

Having described my invention I claim:— 105

1. A shirt sleeve provided with a cuff having layers stitched to each other and a wholly detachable extra facing layer secured directly to and against one side of the cuff externally of the first named layers by 110

- auxiliary stitching extending through the marginal edge portion of said extra facing and the marginal edge portions of the first named layers, and adapted to be wholly detached from said cuff by the removal of said auxiliary stitching, whereby the layers of the cuff will remain permanently secured to each other and the outer face of the layer against which the extra facing is secured 10 will be completely exposed by the removal of said extra facing.
2. A shirt having a sleeve provided with a cuff foldable on itself, the cuff having a facing layer, and a detachable facing layer 15 stitched directly to the first named facing layer and having its edge portions inturned upon itself to permit of its own complete removal without disturbing the attachment of the first named facing layer.
3. A shirt having a sleeve provided with a cuff, the cuff having companion facing layers secured to each other, said layers having button holes formed therein, and a wholly detachable facing layer having its 20 edges inturned upon itself and secured by said inturned edges to the edges of the cuff and provided with button holes secured at

spaced points to the button holes of the cuff to maintain both sets of button holes in normal registration, the detachable facing layer being wholly detachable with its inturned edges by the removal of the means connecting said edges to the cuff and the removal of the means connecting the button holes to the button holes of the cuff. 30 35

4. A shirt having a wear resisting dress portion carrying a facing and an extra layer having its edge portions turned in and disposed against the facing, said extra layer being coextensive with the facing, the facing 40 being secured to the body of the shirt, by stitching extending through the marginal edge portions thereof, and stitching extending through the inturned edge portions of the extra layer and the marginal edge portions of the facing independently of the first stitching and removable independently of said first stitching to permit of the complete detachment of the extra layer, whereby the facing normally concealed by said extra 45 50 layer will be exposed to view and wear.

Signed by me at Springfield, Mass.

EDWARD A. JODOIN.
